Primary Examiner — April Rivas*Assistant Examiner* — Tia Ruth-Renee Polidori(74) *Attorney, Agent, or Firm* — Larson & Larson; Justin P. Miller; Frank Liebenow(57) **CLAIM**

The ornamental design for a cooktop cover, as shown and described.

DESCRIPTION

FIG. 1 is a perspective view of a cooktop cover showing the new design;

FIG. 2 is a detail view of area circumscribed within FIG. 1; FIG. 3 is a top plan view of the cooktop cover of FIG. 1; FIG. 4 is a bottom plan view thereof;

FIG. 5 is a detail view of area circumscribed within FIG. 4; FIG. 6 is a right-side elevation view of the cooktop cover of FIG. 1;

FIG. 7 is a left-side elevation view thereof;

FIG. 8 is a front elevation view thereof;

FIG. 9 is a rear elevation view thereof; and,

FIG. 10 is a detail view of area circumscribed within FIG. 9.

The cooktop cover is shown with symbolic straight-line breaks. The appearance of any portion of the cooktop cover between the symbolic break lines described above forms no part of the claimed design.
